UNITED STATES PATENT OFFICE.

ARTHUR L. HALLIDAY AND JOHN B. NEIL, OF NEW YORK, N. Y., ASSIGNEES TO THE BIGELOW CARPET COMPANY, OF CLINTON, MASS.

DESIGN FOR CARPET.

SPECIFICATION forming part of Design No. 12,210, dated March 29, 1881.

Application filed February 3, 1881. Term of patent 3½ years.

To all whom it may concern:

Be it known that we, ARTHUR L. HALLIDAY and JOHN B. NEIL, of the city of New York, county of New York, and State of New York, have invented a new and original Design for a Carpet, of which the following is a specification.

This invention relates to a new and original design for carpets and similar fabrics; and it consists in the novel grouping and configuration of figures hereinafter more fully described.

The accompanying photograph illustrates a face view of a carpet having our new design.

C is an ornamented stripe containing the circular figures b.

Above the stripe C is the broader stripe A, containing fan-like figures a and flower-like figures i, figures a and i being separated from each other at their lower parts by irregular figures l, and at their upper parts by regular patterned figures g.

Above the stripe A is another stripe, B, having in it circular figures d, occurring at intervals in a patterned stripe, D. Each figure d has set upon it a bud-like figure, f, and these figures f alternate on the stripe, with rectangular figures j.

The stripe E is above the stripe B, and on its background shows flower-like figures e, set above the figure f of the stripe B, alternating with rosette-like figures k, projecting out of the figures j of the stripe B.

The stripes C, A, B, and E are connected by the successive figures b, a, d, f, and e, situated one above the other, to form a continuous design running through the stripes, and also by the figures i, d, f, and e, forming a continuous design running through the respective stripes, and also by the figures k and j, forming a continuous design through the stripes E and B.

We claim—

1. The design for carpets, consisting of the figure a, substantially as shown.
2. The design for carpets, consisting of the figure i, substantially as shown.
3. The design for carpets, consisting of the stripe C, containing figures b, substantially as shown.
4. The design for carpets, consisting of the stripe A, containing figures a, g, e, and i, substantially as shown.
5. The design for carpets, consisting of the stripe D, containing figure d, substantially as shown.
6. The design for carpets, consisting of the figure f, substantially as shown.
7. The design for carpets, consisting of the stripe B, containing figures d f j and band D, substantially as shown.
8. The design for carpets, consisting of the figure e, substantially as shown.
9. The design for carpets, consisting of the figure k, substantially as shown.
10. The design for carpets, consisting of the stripe E, containing figures e and k, substantially as shown.
11. The design for carpets, consisting of the figures b, a, d, f, and e, substantially as shown.
12. The design for carpets, consisting of the figures k and j, substantially as shown.
13. The design for carpets, consisting of the figures i d f e, substantially as shown.
14. The design for carpets, consisting of the stripe E, containing figures e and k, stripe B, containing figures f, d, j, and D, stripe A, containing figures a, g, l, and i, and stripe C, containing figures b, substantially as shown.

ARTHUR L. HALLIDAY.
JOHN B. NEIL.
